UNITED STATES PATENT OFFICE.

ALBERT M. WOLTZ, OF BALTIMORE, MARYLAND, ASSIGNOR TO SOLOMON HIMMEL, OF BALTIMORE, MARYLAND.

DOOR-EQUALIZER.

1,348,680.

Specification of Letters Patent.

Patented Aug. 3, 1920.

Application filed September 17, 1918. Serial No. 254,527.

To all whom it may concern:

Be it known that I, ALBERT M. WOLTZ, a citizen of the United States, residing at Baltimore, State of Maryland, have invented 5 new and useful Improvements in Door-Equalizers, of which the following is a specification.

This invention is an equalizing device for doors of the type employed in connection 10 with sectional furniture, such as book cases, store shelving and display cases, and the like.

One of the objects of the invention is to provide a simple device for preventing the binding of the door during its sliding movement into and out of the sectional unit to which it is attached. A further object is to provide simple means whereby the equalizer and the door may be readily connected in operative relation, or disconnected for purposes of repair or replacement of parts. A 15 further object is to provide an attaching bracket having means to provide a swinging support for the door when the latter is in closed position, and which is capable of 20 readily disengagement from its complementary member when the door is swung to position to travel horizontally.

The invention will be hereinafter fully set forth and particularly pointed out in the 25 claims.

In the accompanying drawing:

Figure 1 is a top plan view of a sectional furniture unit with the invention applied thereto, the door being shown in closed position. Fig. 2 is a transverse sectional view on the line 2—2 Fig. 1. Fig. 3 is an inverted plan view of the equalizer showing the positions assumed by the parts when the door is open. Fig. 4 is a detail perspective view of 30 the door attaching bracket. Fig. 5 is a detail sectional view illustrating the connection between the equalizer and the furniture unit.

Referring to the drawing, 10 designates a sectional furniture unit, provided with an 45 anchoring member 11, and 12 is the slidable and swinging door which may be of any desired construction. The equalizer is formed of two crossed arms 13 and 14, pivotally connected at their point of intersection, as indicated at 15, the inner end of the arm 14 being pivoted to the anchoring member at 16, the inner end of the arm 13 being pivotally connected with a block 17, slidably mounted in an undercut groove 18, formed

in the under surface of the anchoring member 11.

Attached to the inner face of the door 12 near the upper edge thereof, are brackets 20, there being brackets contiguous to each end of the door. Said brackets are of approximately U-shape, having two arms or branches, the arm or branch 21 having an opening 22 therein, and the arm or bracket 23 having a hook-shaped portion 24. Loosely mounted in the openings 22 of the arms 21 is a rod 25, upon which is slidably mounted a sleeve 26, pivotally attached to the outer end of the equalizer arm 14. A similar sleeve 27 loosely engages the rod, and is held from sliding in any suitable manner, such as by means of staples 28, said sleeve being pivotally connected to the outer end of equalizer arm 13. The end walls of the unit 10 are provided with studs 29 positioned to be engaged by the hooks 24 of the brackets 20.

In assembling, the block 17 is first positioned within the groove 18 and then attached to the inner end of the arm 13. The inner end of the arm 14 is also pivotally connected to the anchoring member at 16. To connect the door, the rod 25 is passed through the openings 22 of the brackets 20, and also passed through the sleeves 26 and 27 after which the staples 28 are applied. Normally the staples 28 and sleeve 27 will hold the rod 25 against longitudinal displacement, but if it should be found necessary to provide additional means to prevent endwise movement of the rod 25, the brackets 20 may be provided with struck up portions 30 which may be easily bent up to a position opposite the contiguous end of the rod. In operation, as the door moves inwardly and outwardly in a horizontal position, the block 17 slides in the groove 18 and the sleeve 26 slides upon the rod 25, thereby accurately maintaining the door with its ends parallel with the ends of the furniture unit, and preventing any lateral play of the door. As a consequence the door 100 may be slid inwardly or outwardly with a smooth uniform movement, and binding thereof is prevented. When the door reaches its outermost position, the hooks 24 engage the stud 29 to limit or arrest the 105 outward movement, and the door is free to pivot upon the rod 25 and the studs 29, so that it may swing to its necessary vertical

85

105

position to close the front of the unit. When it is desired to open the door it is swung to a horizontal position, pivoting upon the rod 25 and the studs 29, and when the swinging movement has been completed it may be moved inwardly in the usual and well known manner. If it should become necessary to remove the door for repair or replacement, the staples 28 are removed, whereupon the 10 rod 25 will be free, so that it may be withdrawn from the sleeves 26 and 27, through one of the openings 22. Of course, if the struck up portions 30 are employed, the one contiguous to said opening 22 must be bent down before the rod can be withdrawn. To reassemble, the foregoing operation is reversed.

Having thus explained the nature of the invention and described an operative manner of constructing and using the same, although without attempting to set forth all of the forms in which it may be made, or all of the forms of its use, what is claimed is:—

25 1. The combination with a slidable and swinging door, of brackets attached to the door, a rod having a loose engagement with said brackets, equalizer members each having one end loosely engaging said rod, means normally preventing movement of one of said ends longitudinally of the rod, and means for supporting the other ends of said equalizer members, said rod being disengageable from said brackets and said 30 equalizer arms by a longitudinal movement.

2. The combination with a door of the character described, of brackets attached to the door, a rod loosely engaging said brackets, crossed equalizer members pivotally 40 connected together and each having one end loosely engaging said rod, means for supporting the other ends of said equalizer members, means normally preventing movement of one end of each equalizer member 45 in a direction longitudinally of the door, and hook members projecting from said brackets, said rod being disengageable from said brackets and said equalizer arms by a longitudinal movement.

50 3. The combination with a door of the character described, of U-shaped brackets attached to the door, one arm of each bracket being of hook shape, a rod loosely engaging the other arms of said brackets, equalizer members each having one end loosely engaging said rod, means for supporting the other ends of said equalizer members, and means normally preventing movement of one end of each equalizer member, in a direction longitudinally of the door, said rod be- 55

ing disengageable from said brackets and said equalizer arms by a longitudinal movement.

4. The combination with an anchoring member of a slidable and swinging door, crossed equalizer arms each having one end engaging said anchoring member, and a removable rod pivotally connecting said door and the other ends of said arms, whereby the door may be disconnected without disengaging the equalizer arms from said anchoring member. 65

5. The combination with an anchoring member of a slidable and swinging door, brackets attached to said door, crossed equalizer arms each having a sleeve on one end and having its other end engaging said anchoring member, and a pivot rod removably engaging said brackets and sleeves. 70

6. The combination with a door of the character described, and an anchoring member, of brackets attached to the door, a rod loosely engaging said brackets, crossed equalizer arms, a sleeve slidably and pivotally engaging said rod and connected with one end of one of said equalizer arms, the other end of said arm being pivotally connected with the anchoring member, and a second sleeve engaging said rod and held against sliding movement, said sleeve being 80 connected with one end of the other arm, the other end of the last mentioned arm being slidably connected with the anchoring member. 85

7. The combination with a door of the character described, and an anchoring member having a groove therein, of brackets attached to the door, a rod loosely engaging said brackets, pivotally connected equalizer arms, means for slidably connecting one end of one of said arms with said rod, means for pivotally connecting the other end of the arm with the anchoring member, means for providing a non-slidable pivotal connection between said rod and one end of the other equalizer member, and a block slidably mounted in the groove of said anchoring member and pivotally connected with the other end of the last mentioned equalizer arm, said rod being disengageable from said 100 brackets and said equalizer arms by a longitudinal movement. 105

In testimony whereof I have hereunto set my hand in presence of two subscribing witnesses.

ALBERT M. WOLTZ.
